Patented July 1, 1969

214,603

TIERED DISPLAY RACK

Melvin Cohen, Passaic, N.J., assignor to Melrose Displays, Inc., Passaic, N.J., a corporation of New Jersey

Filed Nov. 28, 1967, Ser. No. 9,562

Term of patent 14 years

Int. Cl. D6—01

U.S. Cl. D80—10

FIG. 1

FIG. 2

FIG. 3

FIG. 4

FIG. 5

FIG. 1 is a front elevational view of a tiered display rack showing my new design, the rear being identical;

FIG. 2 is a side elevational view thereof, the opposite side being identical;

FIG. 3 is a top plan view thereof;

FIG. 4 is a bottom plan view thereof; and

FIG. 5 is a fragmentary perspective of one corner thereof.

I claim:

The ornamental design for a tiered display rack, as shown and desired,
